UNITED STATES PATENT OFFICE.

BRUNO V. NORDBERG, OF MILWAUKEE, WISCONSIN.

FEED-WATER-HEATING SYSTEM FOR MULTIPLE-EXPANSION ENGINES.

SPECIFICATION forming part of Letters Patent No. 728,282, dated May 19, 1903.

Application filed September 2, 1899. Serial No. 729,294. (No model.)

To all whom it may concern:

Be it known that I, BRUNO V. NORDBERG, a subject of the Grand Duke of Finland, Emperor of Russia, residing at Milwaukee, in the county of Milwaukee and State of Wisconsin, have invented certain new and useful Improvements in Feed-Water-Heating Systems for Multiple-Expansion Engines, of which the following is a specification, reference being had to the accompanying drawings, forming a part thereof.

My invention relates to and is designed to be used in connection with compound triple-expansion, quadruple, and multiple expansion engines, which are all comprehended in the designation "multiple-expansion engines."

The main objects of the invention are to reduce the fuel consumption of such engines and also to permit of the economical use of high-pressure steam.

The invention consists in certain novel features of construction and in the arrangement and combinations of parts, as hereinafter particularly described, and pointed out in the claims.

In the accompanying drawings like letters designate the same parts in both figures.

Figure 1 is a diagram illustrating the application of my improvements to a triple-expansion engine, and Fig. 2 is a similar view showing a modification.

Referring to Fig. 1, A, B, and C designate, respectively, the high, intermediate, and low pressure cylinders, and a, b, and c designate, respectively, the steam-chests and distribution-valves of these cylinders. D is the receiver between the high and intermediate pressure-cylinders. d is the inlet-nozzle or supply connection which admits steam from the boiler to the steam-chest a of the high-pressure cylinder. e is the steam-inlet from the receiver D to the steam-chest b of the intermediate cylinder, and f is the steam-inlet from receiver E to the steam-chest c of the low-pressure cylinder. g is the exhaust-pipe from the low-pressure cylinder to the condenser G, which is shown as a surface condenser, although a jet-condenser may be employed with substantially the same effect. H is the air-pump by which the water formed by condensation in the condenser is discharged into the hot-well I.

The above-mentioned parts are such as constitute a modern triple-expansion engine. 55

In the application of my invention to an engine having the parts above enumerated the following devices may be employed: the heaters J, K, L, and M, the feed-water pumps N, O, P, Q, and R, and the auxiliary valves S S in connection with the low-pressure cylinder C. These devices are arranged and connected with the parts of the engine and boiler (not shown) in the following manner: The discharge-nozzles of the valves S S are 65 connected with the heater K, the heater J is placed in the exhaust-pipe g between the low-pressure cylinder and the condenser, the heater L is connected with the receiver E and the heater M with the receiver D, the 70 feed-water pump N is connected on its suction side with the hot-well I and on its discharge side with the heater J, the pump O is connected on the suction side with the heater J and on the discharge side with the heater 75 K, the suction-pipe of pump P is connected with the heater K and its discharge-pipe with the heater L, the suction-pipe of pump Q is connected with the heater L and its discharge-pipe with the heater M, and finally the suction-pipe of the pump R is connected with the heater M and its discharge-pipe with the 80 boiler, the pumps and heaters, with the cylinders, receivers, and steam-chests of the engine and the boiler, thus forming a complete 85 or continuous circuit or cycle. Instead of the pumps other equivalent devices may be used, and in some cases even gravity connections may be employed between the heaters—as, for instance, between the heaters K and L. 90

The apparatus as hereinbefore described operates as follows: The discharge-water from the air-pump H flows into the hot-well I and is forced by the pump N into the heater J, in which its temperature is raised to that 95 of the exhaust-steam from the low-pressure cylinder C. The heater J is shown in the drawings to be of the tubular closed type; but a heater of the open type, in which the exhaust-steam mingles with the feed-water 100 to be heated, may be employed with substantially the same results. The condenser is represented as being of the surface type; but, as before stated, a jet-condenser may be used with equal advantage. With a jet-condenser, 105 however, only a part of the water discharged

by the air-pump is taken through the heater. After passing through the heater J the feed-water is forced by the pump O into the heater K. If the heater J is of the tubular type, as shown, the pump O may in some cases be dispensed with, the pump N in such cases serving to force the water through the closed water-space in the heater J into the heater K. The heater K is preferably of the open type, in which the feed-water mingles with the steam from which it is to extract the heat. The steam for this heater is taken directly from the working space of the low-pressure cylinder C through the auxiliary valves S S, which are operated from the engine by any suitable mechanism, (not shown,) so that they will open at a point in the piston-stroke later than that at which the main steam - valve closes and will close before the main exhaust-valve commences to open. Communication between the low-pressure cylinder C and the heater K thus takes place during the later part of the expansion period, and the time during which this communication takes place as well as the area of the valves S S and of the pipes connecting them with the heater K are so proportioned that the temperature of the water in the heater K will be raised approximately to that of the steam expanding in the cylinder C at its terminal pressure. A part of the steam issuing from the low-pressure cylinder is thus condensed in the heater K, and the volume of water discharged from said heater is greater by that amount than the volume supplied to it from the heater J. The feed-water at this point in its course through the apparatus is thus raised to a temperature approximately equal to that of the working steam at its terminal pressure in the low-pressure cylinder. In some cases other means may be employed for securing this result. If, for instance, the steam plant includes auxiliary engines, steam - pumps, &c., the exhaust-steam therefrom may be sufficient to heat the total feed-water to a temperature approximately equal to that of the steam at its terminal pressure in the low-pressure cylinder, and in such cases such exhaust-steam may be utilized instead of the exhaust-steam taken from the low-pressure cylinder C, or in case the exhaust-steam from such auxiliary devices or external sources is insufficient to accomplish the desired end an additional heater supplied with such exhaust-steam may either be added to the plant or substituted for one of the heaters J and K. The feed-water is next delivered by the pump P into the heater L, which is supplied with steam from the receiver E, and its temperature is raised in said heater to that of the steam in said receiver, a part of that steam being condensed in the heater. As the pressure of the steam in receiver E is in many cases but little higher than the terminal pressure in the cylinder C, which pressure if open heaters are used will be practically the same as that in the heater K, this heater can be placed at a higher eleva-

tion than the heater L and the water carried from the one to the other by gravity, thus dispensing with the pump P. The water from the heater L is forced by the pump Q into the heater M, which has a steam-supply connection with the receiver D, whereby the temperature of the water passing through the latter heater is raised to that of the steam in said receiver, and a part of such steam is condensed. Finally the pump K forces the water from the heater M into the boiler.

While the foregoing describes my invention as applied to a triple-expansion engine, it is equally applicable to a two - cylinder compound or to engines having four or more cylinders in series. In fact, the greater the number of the cylinders and the greater the number of the steps in the operation of heating the feed-water the greater will be the efficiency of the engine.

Referring to Fig. 2, showing a modification of the apparatus by which the arrangement of the pumping system may be somewhat simplified, tubular or closed heaters K', L', and M' are substituted for the direct or open heaters shown in Fig. 1. In this arrangement of the apparatus the pump N becomes the main feed-pump, which forces the feed-water through all the heaters in series into the boiler, the heaters, their connecting water-pipes, and the boiler, forming in this case a closed system. The upper part of the water-space of the heater J is connected directly with the lower part of the water-space of the heater K', the upper part of the water-space of the heater K' is connected directly with the lower part of the water-space of the heater L', the upper part of the water-space of the heater L' is connected directly with the lower part of the water-space of the heater M', and the upper part of the water-space of the last heater is connected directly with the boiler. The suction-pipes of the pumps O', P', and Q' are severally connected with the lower parts of the steam-spaces of the several heaters with which they are associated, and the discharge-pipes of said pumps connect with the discharge-pipes leading out of the water-spaces of said heaters, so that said pumps in this case serve only to remove from the steam-spaces of said heaters the water formed by condensation therein. As this water of condensation has the same temperature as the steam from which it is formed, it must be forced into the discharge-pipes from the several heaters with which said pumps are associated.

In many cases steam is used for other purposes than driving engines—as, for example, in steam-jackets for heating and other purposes. After the latent heat has been extracted from steam so employed the water formed by its condensation may be discharged into that heater or part of my feed-water-heating system the temperature of which corresponds the nearest to that of the water of condensation.

An auxiliary exhaust connection with valve mechanism may be employed with any or a number of the other engine-cylinders, substantially as shown in the drawings in connection with the low-pressure cylinder, for supplying steam to a heater or series of heaters.

I claim—

1. In a feed-water-heating system for multiple-expansion engines the combination with a series of engine-cylinders and means for primarily heating the feed-water to approximately the temperature of the steam at its terminal pressure in the low-pressure cylinder, of a heater connected with an intermediate part of the steam-space between the main steam supply and exhaust of the engine, and adapted to raise the temperature of the feed-water to approximately that of the steam at the point from which it is diverted to said heater, substantially as and for the purposes set forth.

2. In a feed-water-heating system for multiple-expansion engines, the combination with a series of engine-cylinders and their steam and exhaust connections, of a heater, through which the feed-water passes, having a connection with a cylinder of the engine and valve mechanism controlling said connection and adapted to open after the steam-supply of said cylinder is closed and to close before the main exhaust is opened, substantially as and for the purposes set forth.

3. In a feed-water-heating system for multiple-expansion engines, the combination with a series of engine-cylinders and their steam supply and exhaust connections, of a feed-water heater supplied with steam from the low-pressure cylinder and adapted to raise the temperature of the feed-water approximately to that of the steam from the main exhaust of said cylinder, and a heater, through which said feed-water passes on its way to the boiler, having a connection with the steam-space of the engine between its main steam supply and exhaust, and adapted to further raise the temperature of the feed-water approximately to that of the steam at the point from which it is diverted to said last-mentioned heater, substantially as and for the purposes set forth.

4. In a feed-water-heating system for multiple-expansion engines the combination with a series of engine-cylinders, their steam and exhaust connections, and a condenser connected with the exhaust of the low-pressure cylinder, of a heater located in the exhaust connection between said condenser and cylinder, a pump arranged to force the water discharged from said condenser through said heater, and one or more heaters through which the feed-water passes on its way to the boiler from the first-mentioned heater, each of said last-mentioned heaters having a steam-supply connection with a receiver or part of the steam-space of the engine between its cyl-

inders, substantially as and for the purposes set forth.

5. In a feed-water-heating system for multiple-expansion engines the combination with a series of engine-cylinders, their steam supply and exhaust connections, and a condenser connected with the main exhaust of the low-pressure cylinder, of a heater located in the exhaust connection between said condenser and cylinder, an auxiliary exhaust leading from said cylinder, valve mechanism adapted to open said exhaust after steam is cut off from said cylinder and to close the same before the main exhaust is opened, a heater connected with said auxiliary exhaust, and means for forcing the feed-water through said heaters on its way to the boiler, substantially as and for the purposes set forth.

6. In a feed-water-heating system the combination with an engine-cylinder having a main and an auxiliary exhaust, of a heater, through which the feed-water is conducted on its way to the boiler, connected with and supplied with steam from said auxiliary exhaust, and valve mechanism adapted to open the auxiliary exhaust after steam is cut off from said cylinder and to close said exhaust before the main exhaust is opened, substantially as and for the purposes set forth.

7. In a feed-water-heating system for multiple-expansion engines, the combination with a series of engine-cylinders, their steam and exhaust connections, and a condenser connected with the main exhaust of the low-pressure cylinder, of a heater located in the exhaust connection between said cylinder and condenser, a heater connected with an auxiliary exhaust of said cylinder, valve mechanism adapted to open said auxiliary exhaust after the steam-admission valve of said cylinder closes and to close the same before the main exhaust-valve opens, one or more heaters each having a steam-supply connection with a receiver or the steam-space of the engine between its cylinders, feed-water connections between the several heaters, and means for forcing the water discharged by the condenser through said heaters into the boiler, substantially as and for the purposes set forth.

8. A feed-water-heating apparatus having provisions for subjecting the feed-water successively to different degrees of temperature, in combination with a plurality of different heaters connected with said apparatus and adapted to furnish heat thereto at said different temperatures, said heaters being respectively connected with the exhausts of a plurality of different-pressure steam-engine cylinders.

In witness whereof I hereto affix my signature in presence of two witnesses.
